CLAIM

The ornamental design for a portable wireless telephone with a small camera, as shown.

DESCRIPTION

FIG. 1 is a perspective view of the front and right side of a portable wireless telephone with a small camera showing our new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.
